UNITED STATES PATENT OFFICE

ALFRED B. DICKEY, OF FORT WORTH, TEXAS, ASSIGNOR, BY DIRECT & MESNE ASSIGNMENTS, TO GULF PRODUCTION COMPANY, OF FORT WORTH, TEXAS, A CORPORATION OF TEXAS

BLUE PRINTING APPARATUS

Application filed November 26, 1928. Serial No. 321,992.

This invention relates to improvements in blue printing apparatus wherein reaches or portions of sensitized paper are fed from a supply of such paper and positioned on a tracing previously placed over an exposure opening that has associated therewith a suitable source of light for effecting the printing.

One object of the invention is to eliminate the necessity of providing a "dark room" in which to use the apparatus. Stated more specifically, the invention consists in housing the supply of sensitized paper in a light-proof casing mounted on the contact pad 15 that is generally used for pressing the paper against the tracing from which the print is to be made. By having the supply of sensitized paper carried on the contact pad, said pad may be swiveled on its support so as to permit said pad to be rotated, whereby the paper may be positioned across the exposure opening at any desired angle.

In the preferred embodiment of the invention, the pad is also provided with means for holding the paper under tension against the face of the pad and means are also provided on the pad for facilitating severing each portion of the paper as it is exposed. The exposure opening is formed in the top of a table or the like that is quite large compared with the area of opening whereby large tracings, of which only a small portion is to be duplicated, may be easily handled in the machine. In view of this said table top or other support for the tracing is also formed with depressions at opposite sides of the exposure opening for receiving and holding the rolled end portions of a large tracing from the intermediate portion of which a print is to be made.

With these and other objects in view, the present invention consists of certain novel details of construction and combinations and arrangements of parts, all as will herein-after be more fully described and the novel features thereof particularly pointed out in the appended claims.

In the accompanying drawings, illustrating the preferred embodiment of the invention,

Figure 1 is a perspective view of the apparatus from one end thereof;

Fig. 2 is a similar view from the opposite end, the lamp mechanism or source of light being omitted; and

Fig. 3 is a longitudinal sectional view of the contact pad.

In accordance with general practice the apparatus comprises a table whose top 10 has an exposure opening 11 therein, there being a mask 12 around the edge of said opening. Suitably supported beneath the table is a source of light, but as this may be of any desired type it is only shown more or less diagrammatically in the present instance. As indicated, it may be in the form of an arc lamp whose carbons 14 extend into the casing 13. A fan 15 is also provided for circulating air along the bottom surface of the glass 16 in the exposure opening to prevent overheating of the latter.

Located above the table top 10 is the contact pad 17 secured by a swivel connection to an arm 18 forming an extension of an upright supporting member consisting of two sections, one of which 19 is rotatably supported in the other section 20 which is slidably supported in guides 21 on suitable cross pieces of the table. At its lower end section 20 is connected to a foot lever 22 fulcrumed on a cross bar 23. As will be apparent, by depressing lever 22 the contact pad may be raised from the exposure opening and if it is desired to retain it in this position without maintaining pressure on said lever, arm 18 and section 19 may be rotated until the lug 24 on said section is positioned over an abutment 25 on the table. This abutment consists of a block formed with a slot 26 into which lug 24 moves when the pad is lowered to the position it occupies when printing. The swivel connection between the pad and arm 18 may consist of a flange 27 on the post 28 which carries the pad, said flange having a series of holes 29 therein, any one of which may be engaged by a pin 30 removably carried by the arm 18. Preferably, arm 18 has an ordinary T-joint at its end loosely receiving the post

28 whose upper end projects above the joint and has a cap 31 secured thereon.

In order to eliminate the necessity of using the apparatus in a dark room, as well as to facilitate manipulation of the sensitized paper, the supply of such paper, preferably in the form of a roll 32 rotatably supported in brackets 33 on the pad, is housed within 10 a closed casing 34 on said pad. The paper is fed through a slot 35 in the pad at one end thereof beneath casing 34 and in said slot, as well as at the opposite end of the pad, there are spring metal clips 36, 37, by 15 means of which a portion or reach of the paper may be held under tension along the bottom face of the pad. The clip 37 in clamping the paper, cooperates with a knife 38 secured to the pad so that as each increment or portion of paper is exposed and pulled through between said clip and knife, it can be easily severed. Clip 37 is mounted on a guard 39 on the pad.

With this arrangement, there is practically no wear on a tracing regardless of the number of prints made therefrom because each time an exposure is made, the pad can be slightly elevated by pressure on the foot lever, so that there is no rubbing against 20 the tracing while the next succeeding portion of paper is being positioned on the bottom of the pad. For the same reason, the position of the tracing with respect to the exposure opening remains unaffected by the 25 movement of the paper along the face of the pad. It will be understood, of course, that the casing is removable to allow replenishment of the paper.

As before mentioned, it is oftentimes desired to reproduce only small sections of an intermediate portion of a large tracing. To facilitate handling of such large tracings, depressions 40 are formed in the table top at opposite sides of the exposure opening 30 and when an intermediate portion of a large tracing is placed over the opening the rolled end portions thereof are placed in said depressions and thereby held against unrolling. Large tracings can, therefore, be handled with a great deal more ease than if the table top is perfectly plane.

What is claimed is:

1. In a blue printing apparatus, the combination of a table having an exposure opening, a source of light below said table, a contact pad carried above and disconnected from the table, a closed casing on said pad for a supply of sensitized paper, said paper being adapted to be fed along the bottom surface of said pad, and clips carried by said pad at each end for holding the reach of paper under tension along said bottom surface.

2. In a blue printing apparatus, the combination of a table having an exposure

opening, a source of light below said table, a contact pad carried above the table and disconnected therefrom, a closed casing on said pad for a supply of sensitized paper adapted to be fed along the bottom surface of the pad, clips located at each end of the pad for holding the paper under tension, and a knife on said pad cooperating with said clip at the forward end of the pad for facilitating severance of portions of the paper fed from said casing.

3. In a blue printing apparatus, the combination of a table having an exposure opening, a source of light below the table, a contact pad located above the table, a support for said pad and a casing on said pad for housing a supply of sensitized paper adapted to be fed along the bottom surface of the pad, said pad being swiveled on its support whereby a reach of paper along the bottom surface of said pad can be positioned across said exposure opening at any desired angle.

4. In a blue printing apparatus, the combination of a table having an exposure opening therein, a source of light below said opening, a contact pad above the table, a vertically movable support for said pad, said support being rotatable to adjust the pad horizontally of the table and said pad being rotatably secured to its support, and means for positioning a reach of sensitized paper on the bottom face of said pad.

5. In a blue printing apparatus, the combination of a table having an exposure opening therein, a source of light below said opening, a contact pad above the table, a vertically movable support for said pad, said support being rotatable to adjust the pad horizontally of the table and said pad being rotatably secured to its support, a closed housing on said pad for a supply of sensitized paper adapted to be fed along the bottom surface of said pad, and means for positioning said paper on said bottom surface under tension.

6. In a blue printing apparatus, the combination of a table having an exposure opening therein and depressions therein at opposite sides of said opening adapted to receive unrolled portions of a tracing laid across said opening, a source of light associated with said opening, and a contact pad adapted to position a strip of sensitized paper against the portion of the tracing across said opening.

7. In a blue printing apparatus, the combination of a table having an exposure opening in one surface thereof, a source of light below the table, a contact pad carried above the table and adjustable in a plane parallel to said table surface and a closed casing on said pad for a supply of sensitized paper.

8. In a blue printing apparatus the com-

bination of a table having an exposure opening therein, a source of light beneath said table, a vertically movable contact pad carried above the table, said pad being adjustable in a horizontal plane, and a closed casing on said pad for a supply of sensitized paper.
